UNITED STATES PATENT OFFICE.

ISAAC E. PALMER, OF MIDDLETON, CONNECTICUT.

DESIGN FOR FABRIC FOR HAMMOCKS.

SPECIFICATION forming part of Design No. 36,618, dated November 3, 1903.

Application filed October 9, 1903. Serial No. 176,447. Term of patent 14 years.

To all whom it may concern:

Be it known that I, ISAAC E. PALMER, a citizen of the United States, and a resident of Middletown, in the county of Middlesex and State of Connecticut, have invented a new, original, and ornamental Design for a Fabric for Hammocks, of which the following is a specification.

The accompanying drawing illustrates a fabric for hammocks having my new, original, and ornamental design thereon, such illustration rendering the same clear without further description.

What I claim is—

The ornamental design for a fabric for hammocks, substantially as herein shown.

In testimony that I claim the foregoing as my invention I have signed my name, in presence of two witnesses, this 1st day of October, 1903.

ISAAC E. PALMER.
